2,481,636

DEVICE FOR INJECTING PENICILLIN OR
SIMILAR LIQUIDS

Harry Gilbert Willis, Wayville, South Australia, Australia, assignor to A. M. Bickford & Sons Limited, Adelaide, South Australia, Australia, a company of South Australia

Application March 8, 1948, Serial No. 13,577
In Australia April 21, 1947

3 Claims. (Cl. 128—218)

1

This invention relates to an improved device for injecting penicillin or similar liquids.

It is well known that penicillin in oil, or similar relatively viscous liquids, are difficult to inject through the ordinary medicinal syringe for the reason that the liquid cannot be readily drawn into the syringe and in some cases must be heated to enable filling of the syringe.

Heating is undesirable in the case of penicillin which deteriorates under these conditions and according to an earlier invention of mine it has been proposed to store and distribute the penicillin or the like in containers which are provided at one end with means whereby they can be engaged on the butt end of the syringe when the needle is removed therefrom and a plunger then actuated at the other end to positively force the contents of the container into the syringe, it being possible in this way to handle relatively thick or viscous liquids in that displacement from the container is by positive pressure and not by suction.

This method still makes it necessary to use the ordinary syringe which must be sterilised and dried before use and cleaned after use, and it is therefore the object of this invention to provide means whereby injection can take place directly from the improved container without first having to transfer from the container to the standard syringe.

In order however that the invention may be more clearly understood, it will now be described with reference to the accompanying drawings in which:

Fig. 1 is a perspective view of a device according to this invention, and

Fig. 2 is a central longitudinal section of the device showing a container and needle in place as when effecting an injection.

A hollow body 1 formed by bending a strip of metal has at its one end a cap 2 which serves to take a double ended hollow connector 3 tapering outwardly from a screw threaded central section 4 which engages in the cap 2.

The hollow body 1 is of a sufficient size to take the container 5 of penicillin or the like, the body being tapered at the cap end to engage a resilient closure 6 disposed on the discharge end of the container 5, the inner face of the cap 2 engaging this resilient closure to lock the container in position and effect the required seal.

The part 8 of the connector 3 is adapted, when the container 5 is placed into position, to be forced into an aperture 9 in the resilient closure 6 of the container, part 10 of the connector 3 be-

ing adapted to take a needle 11. Different size connectors can be provided to fit different needles or different containers.

Disposed through an aperture at the other end 5 of the hollow body 1 in which the container 5 is held is a stem 14 carrying a piston 15 at its one end which is adapted to fit into the container 5 to actuate a wad or piston 16 disposed within such container, the length of the stem 14 being such that when pressure is applied to its external end, which is provided with a flange or press means 17, the wad 16 within the container 5 is pushed forward to cause the penicillin or the like to be forced out of the container 5 through the hollow connector 3 and thus into and through the needle 11; the stem 14 being stopped when the wad 16 within the container 5 reaches the end of such container.

Finger grips 18 are provided on the rear end of the hollow body 1 in a manner somewhat similar to a syringe.

To allow the containers 5 to be positioned or removed, the hollow body 1 is provided with means whereby the body may be sprung outwardly, such means comprising an end 20 having through it an aperture 21 in which is engaged a tongue 22 projecting from the other end 23. This arrangement allows the body 1 to be opened out by distorting the metal of the body 1 to cause the tongue 22 to be disengaged from the aperture 21. To prevent the body from collapsing inwardly too far when pressure is applied to the finger grips 18 during an injection, a tongue 25 is provided which projects down into the path of the end 20 of the body.

35 The described device can of course be materially varied in its construction but the underlying principle consists in providing a body 1 in which a container 5 of penicillin or the like can be held and which incorporates means whereby a connector 3 is projected into an aperture 9 through the closure 6 at the end of the container 5, pressure means such as the stem 14 and piston 15 allowing the penicillin or the like to be forced out of the container 5 through the connector 3 and into and through the needle 11.

40 In this way a device is provided which can be used to effect the actual injection of the content of the container, the penicillin or the like requiring no transfer from its initial container to any other container and thereby greatly enhancing the hygienic aspects while at the same time removing the need of cleaning and sterilising a syringe. The operation of filling the usual syringe is also entirely removed. The connector 5 is made detachable so that this can be sterilised,

it being possible to carry this in a small sterile container and to position same just before use, thus obviating the need of complete sterilisation of the unit. The connector 3 can be taken from the sterile container by engaging the needle 4 on the connector 3 and then screwing the connector into the cap 2, thus avoiding direct handling of the sterile connector.

Another advantage is that the container of penicillin or the like can still be used with the normal syringe if such is thought desirable or necessary.

What I claim is:

1. For injecting penicillin or similar liquids from a container having an apertured resilient closure at one end and movable plug means within same, improvements comprising; a body formed of strip material to accommodate the container and grip the resilient closure, locking means on the body to hold the body to grip the resilient closure but disengageable to release the grip on the resilient closure, a hollow connector on the body arranged at one end to engage in the aperture in the resilient closure and at the other end to engage a needle, and means on the body to engage the movable plug means.

2. For injecting penicillin or similar liquids from a container having an apertured resilient closure at one end and movable plug means within same, improvements comprising; a body formed of strip material to accommodate the container and grip the resilient closure, finger grips on said body, overlapping ends to the said strip material, locking means between the overlapping ends arranged to be disengaged to open out the body to

release the grip on the resilient closure, stop means to limit closure of the body on to the container, a hollow connector on the body arranged at one end to engage in the aperture in the resilient closure and at the other end to engage a needle, and means on the body to engage the movable plug means.

3. For injecting penicillin or similar liquids from a container having an apertured resilient closure at one end and movable plug means within same, improvements comprising; a body formed of strip material to accommodate the container and grip the resilient closure, finger grips on said body, overlapping ends to the said strip material, locking means between the overlapping ends arranged to be disengaged to open out the body to release the grip on the resilient closure, stop means to limit closure of the body on to the container, a cap on said body, a hollow connector detachably carried by said cap and arranged at one end to engage in the aperture in the resilient closure and at the other end to engage a needle, and means on the body to engage the movable plug means.
